UNITED STATES PATENT OFFICE.

ERSKINE LOWRY SCOTT, OF GRANDVIEW, WEST VIRGINIA.

LATCH.

1,074,750.

Specification of Letters Patent.

Patented Oct. 7, 1913.

Application filed November 28, 1911. Serial No. 662,797.

To all whom it may concern:

Be it known that I, ERSKINE LOWRY SCOTT, a resident of Grandview, in the county of Raleigh and State of West Virginia, have 5 invented certain new and useful Improvements in Latches, of which the following is a specification.

My invention relates to latches, and more particularly to that class of latches which 10 are used in connection with barn doors.

An object of my invention is to provide a latch which may be constructed of inexpensive material and thereby sold at a very 15 low cost.

15 A further object of my invention is to provide a latch which is so constructed as to assure its durability and capability.

With the foregoing and other objects in 20 view, my invention relates to such details of construction and in the arrangement and combination of parts as will be hereinafter fully described and specifically pointed out in the appended claims.

25 In describing my invention in detail reference will be had to the accompanying drawings wherein like characters denote like or corresponding parts throughout the several parts, and in which,

Figure 1 is a plan view of my invention 30 showing the same attached to a door frame and in a locked position. Fig. 2 is a vertical sectional view of my invention as in Fig. 1, however a part of the same is shown in elevation. Fig. 3 is a vertical sectional 35 view of my invention in an open position, parts of the same however shown in elevation.

In the accompanying drawings which 40 fully illustrate the preferred form of my invention, 1 designates a door and 2 designates a door frame of any novel type, I not limiting myself to any specific form whatsoever.

45 Suitably positioned upon the door 1 and preferably near the edge thereof is a keeper 3 which is provided with the cutout portion 4, said cutout portion being provided for a purpose that will presently appear.

Positioned upon the door frame 2 is a base 50 plate 5 on which are formed bolt guiding flanges 6, the said flanges having a lever 7 pivotally mounted therebetween. Formed upon the lever 7 is an elongated extension 8 which extension serves a purpose that will

hereinafter be described. Connecting the 55 forward ends of said flanges is a cross guide bar 9.

I provide an elongated bolt member 10 which has the lugs 11 formed thereon and integral therewith between which lugs is 60 adapted to operate the elongated extension 8 which is formed upon the lever 7 whereby the said member 10 may be slid between the up standing portions 6 and one end of the same may project beyond the member 65 9 and engage the slot 4. I have provided the base plate 1, a lug 12 which limits the backward movement of the member 10 as will be readily recognized upon reference to the drawing. I further provide a member 13 which is preferably constructed of 70 heavy wire, the said member adapted to engage one end of the lever 7 when the same is in the position as shown in Fig. 2 whereby the said lever is held against movement. 75

It is thought from the foregoing disclosure that the operation of my improved latch will be understood. I desire it to be understood that I do not limit myself to 80 any specific member to which my invention is to be attached, that is, I may position a base plate 5 either upon a door or door frame and the bracket 3 on either as well.

From the foregoing it is thought that the 85 advantages and novel features of my improved device will be appreciated.

I desire it to be understood that I may make slight changes in the construction without departing from the spirit of my 90 invention provided such changes fall within the scope of the subjoined claims.

It will be noted that the extension 8 is eccentrically disposed with respect to the pivot of the lever 7. It will also be seen 95 by reference to Fig. 2, that the extension 8 and the adjacent faces of the lugs 11 are so proportioned and shaped as to provide for engagement of the extension 8, securely, with both lugs 11. By reason of this engagement, and also by reason of the lever locking means 13 and the engagement between the cross guide bar 9 on the forward lug 11, the bolt is securely locked in a shot or locked position. 100

105 It will also be noted that there is considerable play between the lugs 11 and the extension 8 in the position shown in Fig. 3, which

play provides for the subsequent locking action of the extension 8, in the position shown in Fig. 2.

Having thus fully described my invention, what I claim as new and desire to secure by Letters Patent is:—

1. In a door fastening means, a keeper carried by the door, a base plate carried by the door frame and having parallel bolt 10 guiding flanges, a bolt slideable on said base plate between said flanges and having lugs spaced apart from each other with the adjacent faces of the lugs diverging from their bases toward their ends, a cross guide bar 15 mounted on said flanges and acting as a stop limiting movement of the bolt in a shot or locking direction and holding said bolt between said flanges, and a lever pivotally mounted on and disposed between 20 said flanges and having an extension lying between said lugs and adapted to actuate said bolt by engagement therewith, substantially as described.
2. In a door fastening means, a keeper, 25 a bolt guiding means, a bolt in said guiding means adapted to be shot into and out of said keeper and provided with lugs having rounded adjacent faces, a lever pivoted on said guiding means and having a cam-

shaped extension eccentrically disposed with respect to the pivot of said lever and arranged to engage both of said lugs when said lever is in a locking position, a stop engaging said bolt when the same is shot, and means for securing said lever in a locking position, substantially as described. 30

3. In a door fastening means, a keeper, bolt guiding means, a bolt in said guiding means adapted to be shot into and out of said keeper and provided with lugs spaced 40 apart from each other, a lever pivoted on said guiding means and provided with a bolt actuating extension reduced in thickness with respect to the space between said lugs to fit loosely therebetween when said bolt 45 is out of a shot position and adapted to engage both of said lugs when the bolt is shot to resist movement of the bolt in opposite directions, and means for holding said lever in a position to shift said extension into engagement with both of said lugs and lock the bolt in a shot position, substantially as 50 described.

E. LOWRY SCOTT.
